UNITED STATES PATENT OFFICE

2,333,217

FUSE CONSTRUCTION

Hugh A. Triplett, Wilmette, Ill., assignor to
Schweitzer & Conrad, Inc., Chicago, Ill., a cor-
poration of Delaware

Original application November 13, 1939, Serial
No. 304,035. Divided and this application June
5, 1942, Serial No. 445,892

6 Claims. (Cl. 200—114)

My invention relates, generally, to circuit inter-
rupters and it has particular relation to fuse
devices of the dropout type. This application
is a division of my copending application Serial
No. 304,035, filed November 13, 1939.

An object of my invention is to provide simple
and efficient means for latching a fuse cartridge
in place in a fuse tube.

Another object of my invention is to provide
for latching the fuse cartridge in place by inter-
action with the same of a single spring biased
latch pin which is movable transversely of the
longitudinal axis of the cartridge.

Other objects of my invention will, in part,
be obvious and in part appear hereinafter.

Accordingly, my invention is disclosed in the
embodiment thereof shown in the accompanying
drawings and it comprises the features of con-
struction, combination of elements and arrange-
ment of parts which will be exemplified in the
construction hereinafter set forth and the scope
of the application of which will be indicated in
the appended claims.

For a more complete understanding of the
nature and scope of my invention, reference may
be had to the following detailed description, taken
in connection with the accompanying drawings
in which:

Figure 1 is a view, in side elevation, of a
dropout fuse device constructed in accordance
with my invention;

Figure 2 is a view, in front elevation, of the
fuse device shown in Figure 1;

Figure 3 is a view, in side elevation, of the
lower contact assembly for the fuse device shown
in Figure 1;

Figure 4 is a view, in front elevation, of the
contact assembly shown in Figure 3;

Figure 5 is a view, partly in side elevation
and partly in section, of the upper contact assem-
bly for the fuse device shown in Figure 1;

Figure 6 is a view, in bottom plan, of the con-
tact assembly shown in Figure 5; and

Figures 7A and 7B, taken together, show the
construction of the dropout fuse tube and asso-
ciated parts, certain portions being broken away
in order to more clearly illustrate the details of
construction.

Referring now particularly to Figures 1 and 2
of the drawings, it will be observed that the ref-
erence character 11 designates, generally, a drop-
out fuse having a channel base 12 on which are
mounted insulators 13 and 14. Upper and lower
contact assemblies 15 and 16 are mounted on
the insulators 13 and 14 and they are provided,

respectively, with circuit terminal members 17
and 18 to permit clamping thereto of the line
conductors. A fuse tube, shown generally at 20,
is provided with upper and lower terminal assem-
blies 21 and 22. The upper terminal assembly
21 is arranged to have contact engagement with
the upper stationary contact assembly 15 while
the lower terminal assembly 22 is arranged not
only to have contact engagement with the lower
contact assembly 16 but is also hingedly mounted
thereon. When a fuse link or fuse cartridge
within the fuse tube 20 blows, as will be described
hereinafter, the upper terminal assembly 21 is
no longer held in the position shown in Figures
1 and 2 of the drawings but is released there-
from to permit the fuse 20 to rotate to the alter-
nate position shown by the broken lines. This
provides a definite air gap between the circuit
terminals formed by the contact assemblies 15
and 16 so that it is unnecessary to rely upon
the gap which is provided by blowing of the fuse
link or fuse cartridge itself.

In Figures 5 and 6 of the drawings the details
of construction of the upper contact assembly 15
are more clearly shown. The upper contact
assembly 15 is provided with a frame member
25 that is arranged to be suitably mounted on
the insulator 13. It has integrally formed there-
with a sleet hood 26 which serves to protect the
mechanism underneath including the upper ter-
minal assembly 21 of the fuse tube 20 from the
elements. Guide clips 27 are secured, as illus-
trated, to the opposite side walls of the sleet
hood 26 for guiding the fuse tube 20 to the cir-
cuit closed position.

Flexible and resilient contact fingers 28 are
provided with out and upwardly turned end por-
tions 29 for contact engagement with the spaced
apart contact surfaces on contact bosses 30, Fig-
ure 7A, forming a part of the upper terminal 21
of the fuse tube 20. As will hereinafter appear,
a portion of this upper terminal assembly 21
moves upwardly when the device is called upon to
interrupt the circuit and, therefore, the outer
ends 29 of the contact fingers 28 and the contact
surfaces of the contact bosses 30 are shaped as
described to facilitate this movement. At their
inner ends the contact fingers 28 are secured, as
by rivets, 31, to the depending sides 32 of a back-
ing member, shown generally at 33. A hinge
pin 34 extending through the depending sides 32
of the backing member 33 and into the depend-
ing side walls of the sleet hood 26 serves to rock-
ably mount the backing member 33 and the parts
carried thereby. A limited degree of freedom

of vertical movement in the contact fingers 28 is thereby provided. It will be observed that the outer end portions 35 of the sides 32 of the backing member 33 are turned outwardly and upwardly to correspond to the outer end portions 29 of the contact fingers 23. Coil compression springs 36 are provided therebetween for biasing the end portions 29 into contact engagement with the contact surfaces of the contact bosses 30, Figure 7A, of the upper terminal assembly 21.

It will now be apparent that the contact fingers 28 have two degrees of freedom. Because of their being rockably mounted on the pin 34, they are movable in a vertical plane. The inherent resiliency of the contact fingers 28 and the springs 36 permit movement in a horizontal plane. As a result close alignment is not required to be maintained between the fuse tube 20 or its mounting in the lower contact assembly 16 and the upper contact assembly 15. This is of considerable advantage not only from a manufacturing but also from an operating standpoint. It is not necessary to provide for mounting the lower terminal assembly 22 of the fuse tube 20 in the lower contact assembly 16 with close tolerances. In the field it is unnecessary to hold the insulators 13 and 14 within close limits of tolerance nor must a great deal of care be exercised in operating the fuse tube 20 to the circuit closed position. When it is recalled that fuse devices of the type disclosed herein are mounted overhead and are intended to be operated by means of switch hooks from a considerable distance, the advantages of these features will be readily apparent.

It is desirable to automatically align the contact fingers 28 with the contact bosses 30, Figure 7A. For this purpose a centering arm 39 is integrally formed with one of the sides 32 of the backing member 33 and is provided with a slotted opening 40, the outer ends of which are flared outwardly, as illustrated in Figure 5, for receiving a guide pin 41, Figure 7A, that is carried by a guide arm 42 forming a part of the upper terminal assembly 21 of the fuse tube 20. When the fuse tube 20 is operated toward the closed circuit position, the guide pin 41 first enters the flared out end portion of the slot 40 and then enters the slot 40 itself to lift the backing member 33 to the extent that may possibly be required. Since there is a definite relationship between the positions of the guide pin 41 and the contact bosses 30 and also between the slot 40 and the contact fingers 28, it will be readily apparent that proper contact engagement will be made between the outer end portions 29 of the contact fingers 28 and the contact surfaces of the contact bosses 30 despite the fact that they might otherwise be considerably out of alignment. The contact surfaces of the outer end portions 29 which are inclined from straight vertical surfaces have a tendency, when pushed in, or as a result of standing in a closed position over a long period of time and being subjected to vibration, etc., to change their relation to each other in a vertical direction. This tendency becomes greater, of course, as the insulation stacks 13 and 14 become higher. It will be noted that the centering arm 39 holds the two contact fingers 28 in a fixed vertical relation with respect to each other after the fuse tube 20 is pushed into place.

With a view to holding the fuse tube 20 in the circuit closed position, a latch arm 43 is provided, Figure 5, that is secured at its rear end by rivets 44 to a bridging member 45 between the sides

32 of the backing member 33. The forward end of the latch arm 43 is split and the two portions thereof are turned at right angles to the remainder of the latch arm 43 as indicated at 46 for receiving therebetween a roller 47. A spring strip 48, secured in position by the rivets 44 which also hold the latch arm 43, serves to bias the roller 47 upwardly, its upward movement being limited by a stop 49 formed by a depending flange of the backing member 33. It will be understood that the roller 47 is adapted to be engaged by a latch hook 50, Figure 7A, forming a part of the upper terminal assembly 21 of the fuse tube 20. Since the latch arm 43 and the roller 47 carried thereby move with the backing member 33, the roller 47 is automatically centered with the latch hook 50 when the guide pin 41 enters the slot 40 in the centering arm 39.

In order to provide a good electrical connection between the backing member 33 and the frame 25 a flexible shunt 51 is provided comprising several layers of flexible copper strips. The flexible shunt 51 is secured at one end by rivets 52 to a bridging member 53 between the sides 32 of the backing member 33. At its other end it is secured to the frame 25 by rivets 54.

The downward movement of the backing member 33 and the parts carried thereby about the hinge pin 34 is limited by a stop 55. It will be noted that the stop 55 is provided by a lug that may be cast integrally with one of the side walls of the sleet hood 26.

In Figures 3 and 4 of the drawings the details of construction of the lower contact and hinge assembly 16 are illustrated. The assembly comprises a housing 60 that is open at the front and has a wall 61 closing the top and side walls 62 depending therefrom. A rear wall 63 joins the walls 61 and 62, as shown. The assembly 16 serves not only to rockably mount the fuse tube 20 but also to conduct current to the lower terminal assembly 22.

In order to rockably mount the fuse tube 20, the side walls 62 are provided with slotted openings 64 for receiving therein trunnions, one of which is shown by a broken line at 65 in Figure 7B of the drawings as forming a part of the lower terminal assembly 22. When the fuse link or cartridge within the fuse tube 20 blows, the fuse tube 20 is unlatched at its upper end, as previously described, and rotates downwardly with the trunnions 65 turning in the bottoms of the slots 64. A rubber bumper 66 is provided for cushioning the inward swing of the fuse tube 20. Disengagement between the fuse tube 20 and the hinge and contact assembly 16 is prevented by interfitting flanges 67 and 68. The flanges 67 are formed integrally with the side walls 62 and project inwardly therefrom while the flanges 68, one of which is shown by broken lines in Figure 7B, are integrally formed with the lower terminal assembly 22. It will be understood that, when the fuse tube 20 is in the circuit-closed position, the flanges 67 and 68 overlap, thereby preventing the recoil resulting from the blowing of the fuse link or cartridge causing the fuse tube 20 to move upwardly and possibly carry the trunnions 65 out of the slots 64. It is only when the fuse tube 20 has rotated to the broken line position shown in Figure 1 that it is possible to lift it out of the slots 64. Likewise, it can only be inserted therein by being initially placed substantially in this position.

Contact engagement with the lower terminal assembly 22 is provided by an inverted U-shaped

contact finger 69 that may be secured by rivets 70 to the rear wall 63 of the housing 60, which pass through one leg thereof. As shown, the outer end of the other leg of the U-shaped contact finger 69 is turned back on itself as indicated at 71 to provide a curved surface for contact engagement with a contact shoe 72, Figure 7B, that is part of a contact arm 73 which extends from the lower terminal assembly 22 into the housing 60 when the fuse tube 20 is in the circuit closed position. An inverted U-shaped spring strip 74, conforming generally to the shape of the contact finger 69 and having one leg commonly secured to the rear wall 63 therewith by the rivets 70, is provided for biasing the other leg of the contact finger 69 outwardly into contact engagement with the contact shoe 72. While the contact finger 69 itself is resilient, the added resiliency of the spring strip 74 serves to bias the portion 71 into high pressure contact engagement with the contact shoe 72.

While it is desirable to bias the contact finger 69 into high pressure contact engagement with the contact shoe 72, it is desirable that there be little movement of the turned back portion 71 required for effecting this high pressure contact engagement. Therefore, a pin 76 is provided through the turned back portion 71, its ends being secured in the side walls 62. The contact finger 69 and the spring strip 74 are then held in a prestressed condition when the contact shoe 72 is out of engagement therewith. In order to obtain the full biasing effect of the contact finger 69 and of the spring strip 74, it is only necessary for the contact shoe 72 to move the turned back portion 71 out of engagement with the pin 76. Despite the fact that only a slight movement of the contact finger 69 takes place, yet, as soon as it is moved away from the pin 76, the full biasing force of the contact finger 69 and of the spring strip 74 is available for providing the desired high pressure contact engagement. With a view to increasing the flexibility of the contact finger 69 and of the spring strip 74 they are split as indicated at 71 in Figure 4 of the drawings.

In Figures 7A and 7B of the drawings the details of construction of the fuse tube 20 are shown. It will be observed that it comprises an outer sleeve 80 and a lining or inner sleeve 81. Preferably, the outer sleeve 80 is formed of a weather resisting material, such as phenolic condensation product, while the liner or inner sleeve 81 is formed of fiber for reasons now well known to those skilled in the art. If desired, the liner or inner sleeve 81 may be omitted and the outer sleeve 80 alone used. A replaceable fuse cartridge, shown generally at 82, and described in detail in the application of which this is a division, is provided at the lower end of the fuse tube 20 and connection thereto is provided by a flexible cable 83. A coil tension spring 84 is provided for tensioning the fuse cartridge 82 and withdrawing a terminal therefrom as will presently appear.

At their upper ends the flexible cable 83 and the spring 84 are secured to a cable and spring fastener having a flanged head 85, the under surface of which engages a flange 86 of a sleeve 87 that is slidably mounted on a ferrule 88. A cap 89 is threaded on the sleeve, as shown, for clamping the flanged head 85 to the sleeve 87 for securing good electrical contact engagement therebetween. A spring 90, around the upper end of the fuse tube 20 and interposed between

the sleeve 87 and the ferrule 88 serves to bias the former upwardly.

It will be noted that the contact bosses 30 and the latch hook 50 are formed integrally with the sleeve 87. As long as the fuse cartridge 82 remains intact, the sleeve 87 is prevented from moving upwardly under the influence of the coil spring 90. However, as soon as the fuse cartridge 82 blows, the sleeve 87 is no longer restrained but moves upwardly carrying with it the latch hook 50. As previously described, when it moves out of engagement with the roller 41, Figure 6, the fuse tube 20 is then free to swing downwardly to the circuit open position. The upward movement of the sleeve 87 relative to the ferrule 88 is limited by screws 91 which project into suitable slots, not shown, in the ferrule 88. The ferrule 88 is fastened on to the upper end of the fuse tube 20 so that it is rigid therewith. For this purpose transverse pins, one of which is shown at 94, are provided on opposite sides. Thus the guide arm 42, which is integrally formed with the ferrule 88, and the guide pin 41 are rigid with the fuse tube 20.

In order to lift the latch hook 50 from engagement with the roller 41 for the purpose of manually removing the fuse tube 20, a pair of arms are provided, one of which is shown at 95, on opposite sides of the ferrule 88 as a part of an operating lever 96 which is pivoted on a pin 97 that extends through a portion of the ferrule 88, as shown. An eye 98 is formed integrally with the operating arm 96 and is adapted to be engaged by the prong of a switch hook, as will be readily understood. A stop 99, forming a part of the eye 98, on engaging a flange 100 extending from the sleeve 87, serves to prevent upward movement of the latter when the fuse tube 20 is moved to the closed circuit position.

In Figure 7B the details of construction of the lower terminal assembly 22 are more clearly illustrated. This terminal assembly includes a ferrule 103 that is fixedly secured to the lower end of the fuse tube 20 by suitable means. An eye 105 is integrally formed with the ferrule 103 to receive the prong of a switch hook for placing the fuse 20 in position with the trunnions 65 in the slots 64. It will be understood that the fuse tube is first positioned as shown by the broken lines in Figure 1. The prong of the switch stick is then removed from the eye 105, and placed in the eye 98. The fuse tube 20 is then swung upwardly to the circuit closed position.

It will be observed that the lower end of the fuse cartridge 82 is provided with a recess in the form of a peripheral groove 107 with which a latch pin 108 cooperates to hold the fuse cartridge 82 in place in the lower end of the fuse tube 20 and within the ferrule 103 against the tension force of the coiled spring 84. The latch pin 108 is slidably mounted in an opening 109 which extends downwardly and through the lower end of the ferrule 103 in a suitably integrally formed boss. A fitting 110 is threaded in the lower end of the opening 109 to provide for guiding the latch pin 108 in its movement. The latch pin 108 is biased inwardly so that the inner end interfits with the groove 107 by a coil compression spring 111 which reacts between the inner end 70 of the fitting 110 and a flange 112 which may be integrally formed with the latch pin 108. A head 113 is provided on the outer end of the latch pin 108 to provide a hold whereby it may be withdrawn to release the fuse cartridge 82.

The lower end of the fuse cartridge 82 is pro-

vided with a slight taper 114 so that, when the fuse cartridge is drawn downwardly through the fuse tube 20 to the position shown in the drawings it can readily depress the latch pin 108 until the groove 107 is placed in registry therewith. When the fuse cartridge 82 has been drawn to this position, the latch pin 108 snaps into place and securely holds the fuse cartridge 82 in the position shown.

At its lower end the fuse cartridge 82 is provided with a terminal 115 that is connected by a short length flexible lead 116 to the ferrule 103. As shown, the flexible lead 116 is provided with a metallic terminal 117 having a suitable aperture which permits it to be placed over a stud 118 extending from the ferrule 103. A nut 119 threaded on the stud 118 serves to securely clamp the terminal 117 in place.

It will be observed that, once the fuse cartridge 82 is drawn into the latched position, as by exerting a pull on the flexible lead 116, as is more fully described in my Patent No. 2,226,838, there is no further tension stress applied to the flexible lead 116. This facilitates the connection of the flexible lead 116 to the ferrule 103.

When it is desired to remove the fuse cartridge 82, it is only necessary to grasp the head 113 and withdraw the latch pin 108 slightly against the biasing force of the spring 111. If the fuse cartridge 82 is unblown, the tension spring 84 will immediately tend to retract the fuse cartridge 82 toward the other end of the fuse tube 20. After the fuse cartridge 82 has blown the outer shell thereof can be readily removed after the flexible lead 116 is disconnected from the stud 118 merely by removing the cap 89 and turning the fuse tube 20 up side down and withdrawing the latch pin 108.

Since certain further changes may be made in the foregoing construction and different embodiments of the invention may be made without departing from the scope thereof, it is intended that all matter shown in the accompanying drawings or described hereinbefore shall be interpreted as illustrative and not in a limiting sense.

I claim as my invention:

1. A renewable circuit interrupter comprising, in combination, a tubular housing, a replaceable circuit interrupting device in said housing, latch means extending transversely of said housing and said device for holding the latter in a predetermined position in the former, said latch means extending to a point outside said housing, and means biasing said latch means into latching position.

2. A renewable circuit interrupter comprising,

in combination, a tubular housing, a replaceable circuit interrupting device in said housing, and a biased latch pin movable transversely of said housing and interfitting with a recess in said device for latching the latter in a predetermined position in the former, axial movement of said latch pin outwardly of said housing releasing the latching connection.

3. A renewable circuit interrupter comprising, in combination, a tubular housing, a replaceable circuit interrupting device insertable through one end of said housing, latch means extending transversely through said housing for automatically interlocking with said device when it is moved to a predetermined position at the other end of said housing, and means biasing said latch means into latching position.

4. A renewable circuit interrupter comprising, in combination, a tubular housing, a replaceable circuit interrupting device insertable through one end of said housing, and a spring biased latch pin movable transversely of said housing and interfitting with a recess in said device when it is moved to a predetermined position at the other end of said housing, the latching connection being released by axial withdrawal of said latch pin from said recess.

5. A renewable circuit interrupter comprising, in combination, a tubular insulating housing, a replaceable circuit interrupting device insertable through one end of said housing, a metallic sleeve at the other end of said housing, latch means extending transversely through said metallic sleeve for automatically interlocking with said device when it is moved to a position within said sleeve, and means biasing said latch means into latching position.

6. A renewable circuit interrupter comprising, in combination, a tubular insulating housing, a generally cylindrical replaceable circuit interrupting device insertable through one end of said housing and having a radially outwardly opening recess, a metallic sleeve at the other end of said housing having an opening extending transversely through one side, a latch pin slidably mounted within said opening with the inner end adapted to automatically interfit with said recess when said device is moved to a predetermined position within said sleeve, a spring coaxial with said latch pin for biasing the same into latching position, and a head on the outer end of said latch pin limiting inward movement thereof in the absence of said device and providing a hold whereby said latch pin can be withdrawn to permit removal of said device.

HUGH A. TRIPLETT.
